UNITED STATES PATENT OFFICE.

ELMER ELSWORTH HANNA, OF EVANSTON, ILLINOIS; PHILETUS W. GATES,
CONSERVATOR.

FLUID-PRESSURE RIVETING-MACHINE.

991,440.

Specification of Letters Patent.

Patented May 2, 1911.

Application filed June 15, 1909. Serial No. 502,402.

To all whom it may concern:

Be it known that ELMER ELSWORTH HANNA, a citizen of the United States, residing at Evanston, in the county of Cook and State of Illinois, has invented certain new and useful Improvements in Fluid-Pressure Riveting-Machines, of which the following is a specification.

The invention relates in general to riveting machines, and more particularly to fluid pressure riveting machines of the type covered by United States Letters Patent Nos. 823,273 and 823,274 granted on June 12, 1906.

In riveting machines of the type referred to, the dies are permitted to separate a sufficient distance to admit of the insertion of the material to be riveted, and during the riveting action the dies move toward each other with gradually increasing pressure until the desired maximum pressure has been reached, after which the dies continue to move toward each other with substantially the attained maximum degree of pressure. The distance through which the dies move toward each other at uniform maximum pressure is such that the machine when once adjusted for a given length of rivet and thickness of plate will require no further adjustment for ordinary variations in the lengths of the rivets, sizes of the holes, or thicknesses of the plates.

The object of the present invention is to provide a riveting machine of the type above described, which will be simple in construction, efficient in operation and durable in use. The invention will be more fully described hereinafter with reference to the accompanying drawings, in which the same is illustrated as embodied in a convenient and practical form, and in which—

Figure 1 is an elevational view showing the dies separated; Fig. 2, a view similar to Fig. 1, showing the dies moved together; Fig. 3, an end elevational view looking from the right in Fig. 2; Fig. 4, an enlarged sectional detail; and Fig. 5, a detail view of the lever F.

The same reference characters are used to designate the same parts in the several figures of the drawings.

Reference letter A indicates the supporting frame, to which is connected in any suitable manner a die a of any desired size and shape. A die b which cooperates with the die a is carried in any suitable manner by means of a frame B relatively movable with respect to the supporting frame A. The frame B is preferably made in the form of a bell crank lever and is provided with arms B', B' spaced apart to straddle the frame A. The supporting frame A and movable frame B are pivotally connected as indicated at C. The frame B is provided with ears b', b' between which is pivotally secured the lower end of a link D, which forms one member of a pair of toggle links. The upper member of the pair of toggle links is pivotally supported at its upper end between arms A', A' which project upwardly from and are preferably formed integrally with the supporting frame A. The upper member of the pair of toggle links consists of a pair of links E, E spaced apart at their upper ends by a collar e. A pivot rod E' extends through bearings a', a' in the upper ends of the arms A, A' of the frame A, and through the interposed upper ends of the links E, E and the intermediate collar e.

F indicates the main operating lever, one end of which projects between the lower ends of the pair of links E, E. Alined circular trunnions F' on the opposite sides of the main lever F extend within circular openings in the lower ends of the links E, E. The upper end of the lower link D of the pair of toggle links is provided with a reduced portion d which extends into an opening f formed in the main operating lever F, as clearly shown in Fig. 4. The reduced upper end d of the lower link D is pivotally connected within the socket f in the operating lever eccentrically to the axis of rotation of the trunnions F' of the lever F relatively to the upper links E, E. The

socket *f* is located within the recess in the main operating lever against which the upper end *d* of the lower toggle link *D* engages.

A pair of guide links *G* are pivotally connected to the main operating lever *F* intermediate of its ends, the other ends of the guide links *G* being pivotally connected to the supporting frame *A*.

The end of the main operating lever *F* opposite to its pivotal connections with the toggle links is pivotally connected to the outer end of a piston rod *h* through the medium of the piston rod head *h'*. The piston rod extends into and is pivotally connected with a piston *H* mounted to reciprocate in a cylinder *K*.

K' indicates the cylinder head and *M* a valve casing in which is inclosed a suitable valve *L* for controlling the supply and exhaust of fluid pressure to the opposite sides of the piston *H*.

N, *N'* indicate bail rods for supporting the riveting machine, the lower ends of such rods being pivotally connected to bail cranks *n*, *n'* mounted upon the supporting frame *A*.

The operation of my improved riveting machine above described is as follows: When the parts are in the position shown in Fig. 1, the material to be worked upon is interposed between the dies *a* and *b*. The valve *L* is then actuated to expose the right end of the piston *H* to fluid pressure which moves the piston within the cylinder *K*. The movement of the piston through approximately the first half of its stroke serves, through the medium of the piston rod *h*, main operating lever *F*, and guide links *G*, to straighten the toggle links *D* and *E* until their center lines are substantially parallel, thereby oscillating the frame *B* relatively to the frame *A* and causing the dies to move toward each other with a gradually increasing pressure, and at a gradually decreasing speed. The movement of the dies toward each other then

continues at substantially uniform maximum pressure and with substantially uniform speed during the movement of the piston through approximately the last half of its stroke. The toggling action practically ceases after the movement of the piston through the first half of its stroke, at which time the movement of the dies toward each other has attained a maximum pressure, and the continued movement of the dies toward each other at such maximum pressure during the movement of the piston through the last half of its stroke is due to the separation of the upper and lower members of the toggle links, by reason of their eccentric connection with the operating lever, that is, by reason of the axis of the pivotal connection between the end *d* of the link *D* and the lever *F* being located eccentrically of the axis of the trunnions *F'* of the lever *F*.

It will be observed that by my improved riveting machine the maximum working or riveting pressure is continuous for a considerable distance, so that when the parts inserted between the dies to be riveted are warped or of unequal thickness the pressure will be sufficient to effect the solid riveting of the parts, and that when the plates or parts to be riveted are of slightly different thickness the continuous maximum pressure will effect the secure riveting of the parts together without adjustment. In other words, the distance of travel of the dies at maximum pressure is sufficient to compensate for inequalities in the material being riveted, thereby rendering the machine useful without subsequent adjustment for riveting different thicknesses of material. The gradual increasing pressure and decreasing speed during the first half of the movement of the piston serves to upset the end of the rivet, while the continued maximum pressure completely closes the heads upon the plates or material, forcing the same together and completing the final union thereof.

I claim:

1. In a riveting machine, the combination with a pair of dies, of means for relatively moving said dies toward and away from each other, comprising toggle links, an operating lever to which are eccentrically pivotally connected the adjacent ends of the toggle links, a guide link pivotally connected to said lever, and means for applying power to said lever.

2. In a riveting machine, the combination with a pair of dies, of means for relatively moving said dies toward and away from each other, comprising toggle links, an operating lever to one end of which are eccentrically pivotally connected the adjacent ends of said toggle links, means for applying power to the other end of said lever, and means for guiding said lever during its movement by said power means.

3. In a riveting machine, the combination with a main frame, of a supplemental frame pivotally connected to the main frame, opposing dies on said frames, toggle links interposed between said main and supplemental frames, a fluid pressure cylinder rigidly mounted upon said main frame, a reciprocating piston in said cylinder, a lever to one end of which are eccentrically pivotally connected the adjacent ends of said toggle links and to the other end of which said piston is operatively connected, and a guide link pivotally connected to said lever intermediate its ends and to said main frame.

4. In a machine of the character described, the combination with a main member, of a supplemental member pivotally connected to the main member, a pair of links pivotally supported by brackets on the main member,

a lever extending between and having trunnions engaging bearings in said links, a link pivotally connected at one end to said supplemental member and pivotally connected at its other end to said lever eccentric of the axis of the trunnions thereon, a guide link pivotally connected to said lever, and means for applying power to said lever.

In testimony whereof, I have subscribed my name.

PHILETUS W. GATES,
Conservator for Elmer Elsworth Hanna.
